UNITED STATES PATENT OFFICE.

JOHN E. A. MILLER, OF SAN FRANCISCO, CALIFORNIA.

CHECK-VALVE FOR BOILER-FEED.

1,357,792.

Specification of Letters Patent.

Patented Nov. 2, 1920.

Application filed July 2, 1919. Serial No. 308,192.

To all whom it may concern:

Be it known that I, JOHN E. A. MILLER, a citizen of the United States, and a resident of the city and county of San Francisco, 5 State of California, have invented a certain new and useful Check-Valve for Boiler-Feed, of which the following is a specification.

The invention relates to improvements in 10 check valves for water feed systems for boilers, and has for its primary object the provision of a valve which will minimize the "blow" or "hammer" in feed systems, and in this way reduce the destructive wear 15 upon, and liability of derangement of, the valve and such parts of the pump or engine as are ordinarily ill-affected by hammering, thereby insuring a smooth, even and reliable water feed action.

20 Another object of the invention is to provide a valve of the character described, which is constructed to operate effectively with a relatively short "lift" or "throw" under and against a reduced load so as to insure 25 reliability and smoothness of operation, there being provided novel means for regulating the lift or throw of the valve.

A further object is to provide a cage for 30 the valve, which cage will permit free operation of the valve, allow the stream to flow freely therefrom and securely hold the valve seat against working out of position so that liability of the boiler feed becoming cut off is eliminated.

35 Another object is to provide a valve and its associated parts, all as of the character described, which will be of simple construction, inexpensive and capable of being readily assembled and dis-assembled.

40 The invention possesses other advantageous features, some of which, with the foregoing, will be set forth at length in the following description where I shall outline in full, that form of the apparatus which I 45 have selected for illustration in the drawings accompanying and forming part of the present specification. In said drawings I have shown one form of the apparatus of my invention, but it is to be understood that I 50 do not limit myself to such form, since the invention, as set forth in the claims, may be embodied in a plurality of forms.

Referring to said drawings:

Figure 1 is a vertical sectional view of the 55 valve of my invention.

Fig. 2 is a top plan view of the valve seat.

Fig. 3 is a fragmentary side elevation of the cage or guide.

Fig. 4 is a fragmentary side elevation of the lift regulating stem. 60

Fig. 5 is a bottom plan view of the stem shown in Fig. 4.

Fig. 6 is a side elevation of a grinding tool.

In carrying out my invention, I materially reduce the area of the valve and increase the area of the valve seat so that a large part of the pressure "load" or "blow," which ordinarily falls upon the valve, is taken up by the seat and "pounding" or 70 "hammering" of the valve is therefore minimized. The valve is preferably annular and in the form of a flat ring, and the seat is flat and provided with an annular opening controlled by the valve. The co-operating 75 faces of the valve and seat are flat, of relatively greater area than the ordinary beveled edge valve and its seat, and the stream discharges between the valve and seat both through the opening in the valve 80 and around the outer periphery of the valve. Therefore, only a relatively short lift is needed to effect an adequate opening of the valve and the valve lifts under a reduced load owing to its reduced area, thus providing 85 for smoothness and reliability of operation.

In the present embodiment of my invention, the valve is provided with a casing 1, of conventional form, said casing having an 90 inlet opening 2 at one end and being closed at its other end by a head plate 3. An outlet 4 is provided on one side of the casing and is connected with the boiler feed pipe 5. The casing is reduced in diameter 95 interiorly and near the intake end, as at 6, and the upper end of this reduced portion is formed with an annular recess 7 which receives the valve seat 8.

The seat 8 is in cylindrical form and upon 100 its upper end is formed with an annular laterally-extending flange 9 which flange rests upon the annular shoulder 10, that is formed by the reducing of the casing 1 at its lower end. The upper end of the seat is 105 flat and presents a disk-like face to the valve and an annular opening 12 is formed through the upper end near the periphery thereof. This opening is interrupted at intervals by webs 13 which connect the separated portions of the seat. There is also provided a vertical web portion 14 located

centrally of the seat beneath the upper end or wall thereof. This web portion joins the sides and top of the seat, strengthening the seat generally. It will thus be seen that the 5 seat is in the form of a flat annular ring 15 which is separated from a flat circular central core portion 16 by a series of segmental openings forming the annular opening 12, and joined with the core portion by the 10 webs 13. The core portion is provided centrally with a recess 16^a to receive and center a grinding tool which will be later described.

Mounted upon the seat 8 is a flat annular 15 valve 17 which is provided on its upper face at its outer periphery with an upstanding annular flange 18. This valve is of such diameter that it will overlie the opening 12 in the seat an equal distance on each side of 20 the opening, and in being of annular form permits the streams to pass between its under face and the seat, on both sides thereof, that is, one stream will pass through the center of the valve and the other out between the outer peripheries of the valve and seat.

There is provided means for regulating the lift of the valve, and this means consists of a stem 19 which is vertically adjustably mounted in the casing 1 and at its 30 lower end is adapted to be engaged by the valve. This stem extends through the head plate 3 and through a bushing member 20 that is secured to the head plate. The bushing is provided with a screw threaded extension 21 and the stem is screw threaded as at 22 for coöperation with the extension. The upper extremity of the stem is screw threaded as at 23 so as to receive a suitable 35 handle not shown. At its lower end the stem is enlarged and cored out as at 24, and provided with spaced laterally extending feet 25, the portions of the enlarged portion between the feet being inclined or tapered 40 downwardly and inwardly, as at 26, to permit free flow of water between the feet. The opening or cored out portion 24 is in 45 registration with the opening through the valve, and the space between the feet is likewise in registration with said valve opening. Formed through the wall of the portion 24 are openings 28 through which water that 50 enters the opening 24 escapes. By turning the stem it is raised or lowered as the case 55 may be, and the lift of the valve may be regulated as desired.

Mounted within the casing 1 is a cylindrical cage member 29, the upper end of which is interiorly screw threaded and turned 60 upon a screw threaded boss 30 that depends from the head plate 3, the stem 19 being passed through said boss. The cage is considerably circumferentially spaced from the casing and at its lower end is enlarged and 65 provides a chamber 31 in which the valve

and lower enlarged end 24 of the stem 19 operates. The chamber 31 or lower end of the cage is provided with a series of segmental openings 32 which permit the stream that passes between the feet 25 into the 70 chamber 31 to pass into the casing 1.

On the lower extremity of the cage are provided lugs 33 which rest upon the seat 8 and serve to prevent the seat from working upwardly and out of position. These lugs 75 33 define openings 34 therebetween and the stream which passes out from between the outer peripheries of the valve and seat escapes through said openings into the casing 1. At the upper end of its enlarged portion the cage is provided with an inwardly extending annular flange 35 which terminates slightly spaced from the enlarged portion 24 of the stem 19. Openings 36 are formed in the cage just above the flange 35 80 and permit water which enters the cage through the openings 28 of the stem 19 to pass into the casing 1.

As shown in Fig. 6 there is provided a 90 grinding tool. This tool comprises a screw threaded plug 37 which is formed on its upper side with a screw threaded projection 38 and on its under side with a central projection 39. The threaded projection provides for the connection with and operation 95 by a bit, not shown. The under projection 39 is adapted to engage in the recess 16^a and center the tool when the latter is screwed into place. The wall of the valve opening is threaded as at 40, so as to receive the tool 37. 100

Assuming that the valve is attached to a steam pump, when the boiler pressure lowers, the water feed pressure forces the valve 17 open, the lift of the valve being limited by the engagement thereof with the feet 25 105 on the stem 19. In this connection, it will be noted that the flange 18 provides on the valve a cup-like face in which the feet engage. Inasmuch as the area of the valve is very small as compared to the conventional 110 type of valve, the pressure "blow" is not all taken up by the valve but largely by the core portion 16 of the valve seat, therefore "hammering" of the valve is eliminated. When the boiler pressure rises and exceeds the feed 115 pressure, the valve will be forced back against the seat and closed, the load being mostly taken up as before explained by the seat and hammering is thus avoided. When the valve is open, and it is only necessary 120 that it open or lift a distance considerably less than the ordinary conventional disk valve, one stream flows inwardly between the valve 17 and seat 8 up through the center of the valve, into the opening 28 in the 125 stem 19, and at the same time through the spaces between the feet 25. This stream is thus divided, part going into the opening 28 into the cage 29 and out through the openings 36 into the casing, and the other part 130

through the spaces between the feet 25 into the chamber 31, and from thence through the segmental openings 32 into the casing 1. The other stream from the valve passes outwardly between the valve and seat and through the opening or spaces defined between the lugs 33, into the casing 1. All streams entering the casing pass through the outlet 4 into the feed pipe 5 and from thence

10 to the boiler, not shown.

Thus it will be seen that the valve need have but a short lift and that it carries a relatively light pressure load in opening and closing. As an example, a conventional 15 solid disk valve for an 800 I. H. P. boiler, the valve having a B area $\times$ 180 lbs. pressure, equaling 1065 lbs. and a lift of $\frac{1}{8}$ of an inch, is subjected to a blow equaling 1065 lbs. $\times$ $\frac{1}{8}$ of an inch. With the valve of this 20 invention having a B area $\times$ 180 lbs. pressure equaling 500 lbs. and a lift of $\frac{1}{32}$ of an inch, the "blow" equals only $500 \times \frac{1}{32}$. Therefore, in my valve I have minimized the 25 "load," shortened the lift and eliminated "hammering," all tending to increase the reliability and efficiency of operation of the valve.

I claim:

1. A check valve comprising a valve casing having an inlet opening and an outlet opening, a valve seat adjacent the inlet opening, said seat having an annular port in its upper face, an annular valve controlling the

port, a lift regulating stem vertically adjustably mounted in said casing and adapted at its lower end to be engaged by the valve, and lateral feet on said stem engaging said valve, said feet being spaced to provide passages therebetween, said passages registering with the opening through 35 the center of the valve and with the casing.

2. A check valve comprising a valve casing having an inlet opening and an outlet opening, a valve seat adjacent the inlet opening, said seat having an annular port in its 40 upper face, an annular valve controlling the port, a lift regulating stem vertically adjustably mounted in said casing and adapted at its lower end to be engaged by the valve, and lateral feet on said stem engaging said 45 valve, said feet being spaced to provide passages therebetween, said passages registering with the opening through the center of the valve and with the casing, said stem having its lower end open and registering with 50 the opening through the valve, said stem having apertures formed therethrough to communicate the lower open end thereof with the interior of the casing.

In testimony whereof I have hereunto set 55 my hand at San Francisco, California, this 24th day of June, 1919.

JOHN E. A. MILLER.
